[57] CLAIM

The ornamental design for a pill dispenser, as shown and described.

DESCRIPTION

FIG. 1 is a front elevational view of a pill dispenser, showing my new design;

FIG. 2 is a left side elevation thereof;

FIG. 3 is a rear elevational view, thereof;

FIG. 4 is a right side elevation thereof;

FIG. 5 is a top plan view, thereof;

FIG. 6 is a bottom plan view, thereof;

FIG. 7 is a view similar to FIG. 4, showing the inner tube member in a typical raised position; and,

FIG. 8 is a view similar to FIG. 4, showing the inner tube member rotated 180° from its former orientation; and raised to an alternative position.

FIG. 1.

FIG. 2.

FIG. 3.

FIG. 4.

FIG. 5.

FIG. 6.

FIG. 7.

FIG. 8.
